UNITED STATES PATENT OFFICE.

ALBERT R. THOMSON, OF DERBY, CONNECTICUT.

TREAD MEMBER FOR ANTI-SKIDDING DEVICES.

Application filed March 26, 1925. Serial No. 18,413.

My invention relates to improvements in tread members for anti-skidding devices of the general form that is shown and described in my application filed June 29, 1923, Serial 5 No. 648,584, and the object of my improvement as here set forth has reference specifically to the construction and arrangement of certain elements that are adapted to be used in tread members and contain in the 10 constructive details a single strand of wire that has a return bend, thus providing two strands that are opposed one to the other and positioned side by side, said strands being preferably twisted, and said strands, also, 15 being spaced from one another for the double purpose of producing a yielding or spring effect under conditions of use and of permitting of freely assembling and dis- 20 assembling, the free ends of said strands being bent and shaped to provide some form or hook structure for connection with supporting devices.

In the accompanying drawing:—

Figure 1 is a plan view of a tread member 25 embodying my invention, corresponding to one form that is shown in the application referred to, the connecting hooks for effecting connection with the side chains being shown by broken lines.

Figure 2 is a side elevation of the same, the connecting hook at the free ends of the strands being omitted, and a hook for connection with the loop at the return bend being shown at an intermediate position along 30 the opposed strands.

Figure 3 is a side elevation of a tread element that differs from the form that is shown in Figs. 1 and 2 in that there is no bend in the structure along the axial line.

Figure 4 corresponds to Fig. 5 of the application mentioned, showing a two-part 40 form of construction and involving essentially an adaptation or modification of the structure that is shown and described in the patent issued to Napoleon Rinfrett, March 45 7, 1917, No. 1,217,999.

Figure 5 is a side elevation of a tread element of extended dual form for use with 50 automobile wheel structures of double form and in which the active elements are longitudinally spaced and connected by means of a link or the like the individual elements being longitudinally curved.

Figure 6 is a side elevation and on a reduced scale of a tread member of dual form

and with the end connecting hooks and which has the individual elements of straight form and a connecting link of elongated non-circular form.

My improved tread member for anti-skid- 60 ding devices involves the use of an active member 10 that in particular embodies my invention and that is connected by its ends through the medium of end or connecting hooks 11 of substantially ordinary form to 65 side chains of the usual form.

Said active member 10 is formed of a single piece of wire that is bent back upon itself at or adjacent the middle to provide a loop 12 that is adapted to receive and 70 co-operate with one of the connecting hooks 11 for effecting the end connection at this particular end.

For connecting with the hook 11 at the other end the free ends of the strands may 75 be specially shaped or swaged to provide a hook structure that corresponds with the form that is shown and described in the patent issued to myself under date of November 30, 1920, No. 1,360,600, or some other 80 form that is operative and convenient may be provided.

In the structure that is shown in Figs. 1 and 2 the two strand ends 13 are individually 85 formed into hooks, the two hooks being positioned side by side and turned oppositely, in a manner that is well known.

The two opposed hooks 13 when connected to a connecting hook 11 in the usual manner by being entered through the loop portion 90 14 thereof will be pressed together so as to be in contact, side by side.

As to the relative position of said hooks 13 when the device is free from strain or contact with other parts, this will depend upon 95 the particular setting that is provided therefor in that they may be normally spaced one from the other or may be in contact, a spring or yielding effect being involved in either case.

In the preferred form said hooks 13 are 100 normally in contact, side by side, and to effect connection with the loop portion 14 of the connecting hook 11 they can be forcibly pressed apart.

The individual strands 15 intermediate 105 loop 12 at one end and the hooks 13 at the other end are of proper length to serve as active road-contacting elements; are twisted around one another; and are normally 110

spaced apart, the separating space being generally such as to admit relatively freely the connecting hook 18 that is to be connected with the closed end or loop 12.

5 The active member 10, as mentioned, is made of wire and of spring material.

In the structure that is shown in Figs. 1 and 2 said active member 10 is curved from end to end to correspond generally to the 10 curvature of the face of the tire to which it is applied. Thus in Fig. 2 the middle portion 17 is higher than the end portions 12 and 13.

In the form that is shown in Fig. 3 the 15 active member 10^a has an axial line that is essentially straight and adapted to extend across the active portion of the face of a tire that is essentially flat. In this case the connecting hooks 13^a would meet the terminals 12^a and 13^a at a more pronounced angle in making connection with the side chains and they may be made somewhat longer than hooks of the usual form.

In the structure that is shown in Fig. 4 the 20 active tread structure is made up of two similar and relatively short tread elements 13^b that are connected together by interlocking the opposed loop or return bend portions 12^b.

25 In the structure shown in Fig. 5 a flexible-joint form of structure is provided that differs from that shown in Fig. 4 in the detail that the opposed loops or return bend portions 12^c instead of being directly interlocked are operatively connected through the medium of an intermediate link 18. Such a link may be adapted to provide spacing for the connected active members 13^c so that these can operate as individual tread

devices for the spaced tires of a dual wheel 40 structure.

In the different devices shown the connection with the loop or return bend can be made by spreading apart the hooks at the free ends of the strands; entering the device to be connected between said hooks; and finally slipping said device along the space between the strands to reach the loop or return bend.

Reverting to the form that is shown in 50 Fig. 5, the individual tread elements 10^c differ from the elements 10^b that are shown in Fig. 4 only in the manner of use, said elements being of longitudinally curved form.

55 In the structure that is shown in Fig. 6 the individual tread members or elements 10^d are straight and the connecting link 18^d is of elongated or oval form instead of circular, as in Fig. 5. The hooks 11^d of the form that is shown in Fig. 6 as well as the hooks 11^a of Fig. 3 would be somewhat longer than for the form that is shown in Figs. 1 and 2.

60 I claim as my invention:—

An active tread member for an anti-skidding device made of a single piece of wire that is bent adjacent the middle to provide an open loop and a pair of strands connected to the arms of said loop, the free ends of 70 said strands being swaged to provide a hook structure, the said strands being positioned side by side and twisted, said strands being normally separated one from the other by an open space and the axis of said strands 75 being substantially straight.

ALBERT R. THOMSON.
